Fraenkel and Richards,
ATTORNEYS

UNITED STATES PATENT OFFICE.

FREDERICK PEITER, OF BROOKLYN, NEW YORK.

FURNACE.

1,318,690.

Specification of Letters Patent. Patented Oct. 14, 1919.

Application filed May 28, 1919. Serial No. 50,290.

To all whom it may concern:

Be it known that I, FREDERICK PEITER, a citizen of the United States, residing at Brooklyn, in the county of Kings and State of New York, have invented certain new and useful Improvements in Furnaces; and I do hereby declare the following to be a full, clear, and exact description of the invention, such as will enable others skilled in the art 10 to which it appertains to make and use the same, reference being had to the accompanying drawings, and to characters of reference marked thereon, which form a part of this specification.

15 The present invention relates, generally, to improvements in boiler settings or furnaces; and the invention relates, more particularly, to a novel construction and arrangement of boiler setting or furnace adapted to burn waste, such as bagasse, tan chips, peat, lignite or any fuel having a large content of water, in a manner to develop a high thermal efficiency, and at the same time to so distribute the heat of the flame that no 25 part of the furnace is heated to a point endangering or unduly shortening the life of the refractories.

The invention has for its principal object 30 to provide a boiler setting or furnace comprising three main parts, to wit, a generator to dry and gasify the fuel; a combustion chamber from which there is no direct transfer of heat to the ultimate object to be heated, *e. g.* the boiler, thus insuring a high temperature to the air and the remaining unconsumed combustible gas as it leaves the combustion chamber; and a muffle chamber in which to complete combustion of the gas before it is permitted to contact with the 35 surfaces of the ultimate object to be heated, *e. g.* the boiler.

Another object of the present invention is 40 to provide, in connection with a novel boiler setting or furnace of the character above mentioned, a means for delivering to the combustion chamber a supply of auxiliary or secondary air in preheated condition, the same being adapted to supply additional oxygen for supporting the combustion of 45 gases delivered from the generator, and preventing undue chilling of gases within the combustion chamber which would tend to interfere with its due ignition.

Other objects of the present invention, not 50 at this time more particularly enumerated,

will be clearly understood from the following detailed description of the same.

With the various objects of my present invention in view, the same consists, primarily, in the novel construction of boiler setting, or furnace hereinafter set forth; and the invention consists, furthermore, in the novel arrangements and combinations of the various devices and parts, as well as in the details of the construction of said parts, all of which will be more fully described in the following specification, and then finally embodied in the claims appended thereto:

The invention is clearly illustrated in the accompanying drawings, in which:—

Figure 1 is a longitudinal vertical section through one unit of a boiler setting or furnace made according to and embodying the principles of my present invention.

Fig. 2 is a transverse section taken on line 2—2 in said Fig. 1; Fig. 3 is a transverse section taken on line 3—3 in said Fig. 1; and Fig. 4 is a transverse section taken on line 4—4 in said Fig. 1.

Similar characters of reference are employed in all of the hereinabove mentioned views to indicate corresponding parts.

Before proceeding to a detailed description of the construction of my novel boiler setting or furnace, I will describe the character of fuel it is designed to burn, so that the functions and operation of my invention will be more clearly understood. I will take bagasse as illustrative of the character of fuel which may be utilized in my novel furnace, and what is said with respect to bagasse, is also true with respect to any fuel substance that is composed of cellulose or any fuel of high moisture content.

Bagasse, which is the refuse from sugar mills, has a moisture content of from 45 to 60 per cent., the remainder being cellulose. Taking bagasse with a moisture content of 45 per cent., the remaining cellulose would consist, substantially of 27 $\frac{1}{2}$ per cent. carbon and 27 $\frac{1}{2}$ per cent. inert matter (*i. e.* inert as far as heat value is concerned). The only source of heat in such a fuel is the carbon, the moisture and inert matter being drawbacks. This fuel when gasified in a generator will yield a gas of about the following composition to wit, CO 22 $\frac{1}{2}$ per cent.—CO₂ 1.04 per cent.—N 46.76 per cent.—H₂O (vapor) 29.7 per cent. A gas of this composition at 60° F. (considering the water still

as vapor at this temperature) will have a calorific value of 77.4 B. T. U. per cubic feet. It will be apparent that this fuel provides but a very lean gas containing only about 5 $22\frac{1}{2}$ per cent. of combustible. It will therefore be clear that to use the same advantageously, not only must oxygen contained in secondary or auxiliary air be supplied to support its combustion, but sufficient time 10 must be allowed to permit the molecules of oxygen to find the molecules of combustible, consequently provision must be made for a long flame. The gas thus produced is slow burning and possesses a comparatively 15 low flame temperature, consequently provision must be made to assure that all combustion be completed before it is allowed to come in contact with the comparatively low temperature of the boiler surfaces, particularly 20 since the chemical reaction between the combustible and the oxygen ceases at a comparatively high temperature, and for the further reason that if the combustible cools against the boiler walls it decomposes 25 producing carbon which deposits itself as soot, thus reducing the efficiency of the heat conductivity of the boiler surfaces.

It is a purpose of my present invention to provide a construction and arrangement of 30 furnace which will efficiently generate a gas of the character above described, and which will then control the combustion of such gas in such a way as to provide the most advantageous conditions for securing the best 35 thermal efficiency possible according to the requirements above noted. To this end I provide the following novel construction of boiler setting or furnace.

Referring to the accompanying drawings, 40 the reference character 1 indicates the complete boiler setting or furnace, the same comprising a generator chamber 2 in its forward end, provided with a grate 3 in its lower portion, and a feed hopper opening 4 in its upper or top wall. The side wall of 45 said generator chamber 2 is provided with a primary air intake opening 5 situated beneath the grate 3.

Arranged in back of said generator chamber 2 is a combustion chamber 6, separated from the former by the partition wall 7, in which are the openings or passages 8 leading from the upper end of said generator chamber into the said combustion chamber. Situated in back of said generator chamber 2 and beneath the forward end of said combustion chamber 6 is a secondary or auxiliary air chamber 9, from which extend upwardly into communication with the lower 60 end of said combustion chamber a series of secondary or auxiliary air delivery ports 10. Located in the rear of said combustion chamber 6, and below the same, so that its forward end communicates with said combustion chamber by means of an opening or

passage 11 in the bottom of the latter is a muffle chamber 12, which extends longitudinally beneath the boiler chamber 13, in which the boiler 14 is mounted, and which is divided from said boiler chamber by a horizontal arched partition or muffle wall 15 provided with a plurality of escape ports 16 affording communication between said muffle chamber and said boiler chamber. Embedded in the floor 17 of said muffle chamber 12 is a longitudinally extending secondary or auxiliary air conduit 18 which extends to and discharges air into said secondary or auxiliary air chamber 9. The heat of the flaming gases within said muffle chamber is transmitted by conduction to said conduit 18 so that the temperature of the air passing therethrough into the secondary or auxiliary air chamber 9 is raised or the air is preheated before delivery to the latter, 75 and from the latter into said combustion chamber 6. The heated gases resulting from the process of combustion within said muffle chamber escape through the ports 16 of the muffle wall 15 into the boiler chamber 13, so 80 as to contact with the bottom 19 of the boiler shell, and are thence drawn through the boiler tubes 20, and thence into the draft flue 21.

The bagasse, or other fuel, is deposited 95 through the feed hopper opening 4 into the generator chamber 2, and is piled on the grate 3, there to be ignited and burned, a sufficient quantity of primary air to support the combustion being delivered beneath the 100 grate through the opening 5. The burning of the bagasse within the generator chamber drives off the moisture and gasifies the fuel, producing a combustible, but lean gas, which is vented into the combustion chamber 6 105 through the communicating openings or passages 8. Within the combustion chamber 6 the ignited and burning gas meets with the secondary or auxiliary supply of preheated air delivered from the chamber 9 through the delivery ports 10. Said secondary or auxiliary air being preheated prevents the gas with which it mixes within the combustion chamber from chilling at this first point of combustion, thus assuring 110 115 thorough ignition of the gas, as well as assuring an adequate additional supply of oxygen to support the combustion thereof. The burning gas stream is delivered through the opening or passage 11 into the muffle 120 chamber 12 wherein the combustion is completed, and the high temperature waste gases thence delivered through the muffle ports 16 into the boiler chamber 13 and through the boiler tubes 20 to escape finally through the 125 draft flue 21. The muffle wall 15 serves to hold back the gas within the muffle chamber until each molecule of combustible finds its molecule of supporting oxygen derived from the secondary or auxiliary air, or in other 130

words until combustion of the gas is complete, so that, consequently, unconsumed combustible is reduced to a minimum whereby by the boiler chamber and boiler flues are kept practically clear of soot deposits, and whereby the full thermal efficiency of the gas is attained when finally delivered through the muffle ports into the boiler chamber.

- 10 It will thus be clearly understood that my novel construction and arrangement of boiler setting or furnace provides all the structural necessities for the most efficient use of fuels such as bagasse, or other cellulose containing substances, and other fuels having high moisture content according to the requirements above outlined.

For convenience I provide at the rear end of said muffle chamber, or in other convenient location in relation thereto, an oil burner 22 fed by a supply pipe 22'. This burner may be used to introduce oil fuel into the furnace to supply additional heat if desired to help operating conditions, or 25 to supply all heat when it is desired to stop the gas generation process in order to clean out the generator chamber.

I am aware that some changes may be made in the general arrangements and combinations of the several parts of my novel boiler setting or furnace, as well as in the details of the construction of the same, without departing from the scope of my present invention as set forth in the foregoing specification, and as defined in the appended claims. Hence, I do not limit my invention to the exact arrangements and combinations of parts as described in said specification, nor do I confine myself to the exact details 40 of the construction of said parts as illustrated in the accompanying drawings.

I claim:—

1. In a device of the kind described, a gas generator chamber, a combustion chamber communicating with said generator chamber to receive a generated gas from the latter, means for supplying auxiliary air to said combustion chamber for mixture with said gas, a muffle chamber into which the 50 burning gas is discharged from said combustion chamber, a perforated muffle wall covering said muffle chamber, and a chamber above said muffle wall in which is located the ultimate object to be heated.

55 2. In a device of the kind described, a gas generator chamber, a combustion chamber communicating with said generator chamber to receive a generated gas from the latter, means for supplying auxiliary air to said combustion chamber for mixture with said gas, a muffle chamber into which the burning gas is discharged from said combustion chamber, a perforated muffle wall covering said muffle chamber, a chamber 60 above said muffle wall in which is located

the ultimate object to be heated, and means for preheating said auxiliary air prior to delivery to said combustion chamber.

3. In a device of the kind described, a gas generator chamber, a combustion chamber 70 communicating with said generator chamber to receive a generated gas from the latter, an auxiliary air chamber below said combustion chamber, an intervening wall between said combustion chamber and said 75 auxiliary air chamber provided with a plurality of air delivery ports leading from the latter to the former, a muffle chamber into which the burning gas is discharged from said combustion chamber, a perforated muffle 80 wall covering said muffle chamber, and a chamber above said muffle wall in which is located the ultimate object to be heated.

4. In a device of the kind described, a gas generator chamber, a combustion chamber 85 communicating with said generator chamber to receive a generated gas from the latter, an auxiliary air chamber below said combustion chamber, an intervening wall between said combustion chamber and said 90 auxiliary air chamber provided with a plurality of air delivery ports leading from the latter to the former, a muffle chamber into which the burning gas is discharged from said combustion chamber, a perforated muffle 95 wall covering said muffle chamber, a chamber above said muffle wall in which is located the ultimate object to be heated, and means for delivering preheated auxiliary air to said auxiliary air chamber. 100

5. In a device of the kind described, a gas generator chamber, a combustion chamber communicating with said generator chamber to receive a generated gas from the latter, an auxiliary air chamber below said 105 combustion chamber, an intervening wall between said combustion chamber and said auxiliary air chamber provided with a plurality of air delivery ports leading from the latter to the former, a muffle chamber into 110 which the burning gas is discharged from said combustion chamber, a perforated muffle wall covering said muffle chamber, a chamber above said muffle wall in which is located the ultimate object to be heated, and 115 means for delivering preheated auxiliary air to said auxiliary air chamber comprising an air conduit leading into said auxiliary air chamber embedded in the floor of said muffle chamber. 120

6. In a device of the kind described, a gas generator chamber provided with a grate and means for delivering primary air beneath said grate, the upper wall of said generator chamber having a feed hopper 125 opening through which fuel may be deposited upon said grate, a combustion chamber communicating with said generator chamber to receive a generated gas from the latter, means for supplying secondary air 130

to said combustion chamber for mixture with said gas, a muffle chamber into which the burning gas is discharged from said combustion chamber, a perforated muffle wall 5 covering said muffle chamber, a boiler chamber above said muffle wall, and a boiler mounted within said boiler chamber.

7. In a device of the kind described, a gas generator chamber provided with a grate 10 and means for delivering primary air beneath said grate, the upper wall of said generator chamber having a feed hopper opening through which fuel may be deposited upon said grate, a combustion chamber 15 communicating with said generator chamber to receive a generated gas from the latter, means for supplying secondary air to said combustion chamber for mixture with said gas, a muffle chamber into which the burning gas is discharged from said combustion chamber, a perforated muffle wall 20 covering said muffle chamber, a boiler chamber above said muffle wall, a boiler mounted within said boiler chamber, and means for preheating said auxiliary air 25 prior to delivery to said combustion chamber.

8. In a device of the kind described, a gas generator chamber provided with a grate and means for delivering primary air beneath said grate, the upper wall of said generator chamber having a feed hopper opening through which fuel may be deposited upon said grate, a combustion chamber 30 communicating with said generator chamber to receive a generated gas from the latter, a secondary air chamber below said combustion chamber, an intervening wall between said combustion chamber and said air chamber provided with a plurality 35 of air delivery ports leading from the latter to the former, a muffle chamber into which the burning gas is discharged from said combustion chamber, a perforated muffle wall 40 covering said muffle chamber, a boiler chamber above said muffle wall, and a boiler mounted within said boiler chamber.

9. In a device of the kind described, a gas generator chamber provided with a grate and means for delivering primary air beneath said grate, the upper wall of said generator chamber having a feed hopper opening through which fuel may be deposited upon said grate, a combustion chamber 50 communicating with said generator chamber to receive a generated gas from the latter, a secondary air chamber below said combustion chamber, an intervening wall between said combustion chamber and said air chamber provided with a plurality 55 of air delivery ports leading from the latter to the former, a muffle chamber into which the burning gas is discharged from said combustion chamber, a perforated muffle wall 60 covering said muffle chamber, a boiler chamber above said muffle wall, a boiler

mounted within said boiler chamber, and means for delivering preheated air to said secondary air chamber.

10. In a device of the kind described, a gas generator chamber provided with a grate 70 and means for delivering primary air beneath said grate, the upper wall of said generator chamber having a feed hopper opening through which fuel may be deposited upon said grate, a combustion chamber 75 communicating with said generator chamber to receive a generated gas from the latter, a secondary air chamber below said combustion chamber, an intervening wall between said combustion chamber and said air chamber provided with a plurality of air delivery ports leading from the latter to the former, a muffle chamber into which the burning gas is discharged from said combustion chamber, a perforated muffle 80 wall covering said muffle chamber, a boiler chamber above said muffle wall, a boiler mounted within said boiler chamber, and means for delivering preheated air to said secondary air chamber comprising an air 85 conduit leading into said air chamber embedded in the floor of said muffle chamber.

11. In a device of the kind described, a gas generator chamber provided with a grate and means for delivering primary air 95 beneath said grate, the upper wall of said generator chamber having a feed hopper opening through which fuel may be deposited upon said grate, a combustion chamber 100 communicating with said generator chamber to receive a generated gas from the latter, a secondary air chamber below said combustion chamber, an intervening wall between said combustion chamber and said air chamber provided with a plurality 105 of air delivery ports leading from the latter to the former, a muffle chamber into which the burning gas is discharged from said combustion chamber, a perforated muffle wall covering said muffle chamber, 110 a boiler chamber above said muffle wall, a boiler mounted within said boiler chamber, means for delivering preheated air to said secondary air chamber comprising an air 115 conduit leading into said air chamber embedded in the floor of said muffle chamber, and an oil-burner device operatively mounted in connection with said muffle chamber.

12. In a device of the kind described, a gas generator chamber provided with a grate and means for delivering primary air beneath said grate, the upper wall of said generator chamber having a feed hopper opening through which fuel may be deposited upon said grate, a combustion chamber 120 communicating with said generator chamber to receive a generated gas from the latter, a secondary air chamber below said combustion chamber, an intervening 125

wall between said combustion chamber and said air chamber provided with a plurality of air delivery ports leading from the latter to the former, a muffle chamber into which

5 the burning gas is discharged from said combustion chamber, a perforated muffle wall covering said muffle chamber, a boiler chamber above said muffle wall, a boiler mounted within said boiler chamber, and
10 an oil-burner device operatively mounted in connection with said muffle chamber.

13. In a device of the kind described, a gas generator chamber, a combustion chamber communicating with said generator chamber to receive a generated gas from the latter, an auxiliary air chamber below said combustion chamber, an intervening wall between said combustion chamber and said auxiliary air chamber provided with 15 a plurality of air delivery ports leading from the latter to the former, a muffle chamber into which the burning gas is discharged from said combustion chamber, a perforated muffle wall covering said muffle chamber, a chamber above said muffle wall in which is located the ultimate object to be heated, and an oil-burner device operatively mounted in connection with said muffle chamber.

20

25

30

14. In a device of the kind described, a gas generator chamber, a combustion chamber communicating with said generator

chamber to receive a generated gas from the latter, an auxiliary air chamber below said combustion chamber, an intervening wall between said combustion chamber and said auxiliary air chamber provided with a plurality of air delivery ports leading from the latter to the former, a muffle chamber into which the burning gas is discharged from said combustion chamber, a perforated 40 muffle wall covering said muffle chamber, a chamber above said muffle wall in which is located the ultimate object to be heated, and an oil-burner device operatively mounted in connection with said muffle 45 chamber.

15. In a device of the kind described, a gas generator chamber, a combustion chamber communicating with said generator chamber to receive a generated gas from the latter, means for supplying auxiliary air to said combustion chamber for mixture with said gas, a muffle chamber into which the burning gas is discharged from said combustion chamber, a perforated muffle 50 wall covering said muffle chamber, a chamber above said muffle wall in which is located the ultimate object to be heated, and an oil-burner device operatively mounted in connection with said muffle chamber.

In testimony, that I claim the invention set forth above I have hereunto set my hand this 23rd day of May, 1919.
